(57) **CLAIM**

The ornamental design for a raceway fitting, as shown and described.

DESCRIPTION

FIG. 1 is a perspective view of a raceway fitting showing our new design;

FIG. 2 is an enlarged end view thereof, the opposite end view being identical;

FIG. 3 is a side view thereof, the opposite side view being identical;

FIG. 4 is a top plan view thereof; and,

FIG. 5 is an exploded perspective view thereof.

The broken line showing in the Figures is for illustrative purposes only and forms no part of the claimed design.
